MINING MACHINE

David R. McCullough, Lost Spring, Wyo., assignor
of one-third to William O. Widger, Harrison,
Nebr.

Application August 25, 1936, Serial No. 97,820

4 Claims. (Cl. 262—25)

This invention relates to mining machines and an object of the invention is to provide a mining machine particularly adapted for use in mining coal.

5 A further object of the invention is to provide a mining machine particularly adapted for the undercutting of the coal within the mine.

The invention together with its objects and advantages will be best understood from a study 10 of the following description taken in connection with the accompanying drawings, wherein

15 Figure 1 is a top plan view of the machine showing the conveyors and saws associated therewith.

Figure 2 is a detail view showing certain parts in section and illustrating particularly the manner of anchoring the runners at the desired position within the mine.

20 Figure 3 is a front elevational view of the carriage with the tools and other parts omitted.

Figure 4 is a rear elevational view of the carriage.

25 Figures 5 and 6 are detail sectional views taken substantially on the lines 5—5 and 6—6, respectively of Figure 1.

Figure 7 is a plan view of one of the end bearings.

Figure 8 is a plan view of the ball equipped end of an adjusting screw.

30 Figure 9 is a sectional view through the saw.

Figure 10 is a transverse sectional view through the saw and taken at right angles to Figure 9.

Figure 11 is a detail sectional view taken substantially on the line 11—11 of Figure 1.

35 Figure 12 is an elevational view of the coal cutting bit.

Figure 13 is a similar view of a conveyor auger.

Referring to the drawings by reference it will be seen that the mining tool comprises a pair of 40 runners 5—5 formed of strap metal turned up at their respective opposite ends, or of some other suitable material.

The runners 5 are respectively provided at their respective opposite ends with holes 6.

45 A transverse bar 7 is adapted to extend between the runners 5 at either end of the runners and at its respective opposite ends the bar 7 is provided with openings aligned with the openings 6 to accommodate the spikes 8 provided on the 50 tubular sections 9 of a pair of anchoring jacks indicated by the reference numeral 10.

As shown in Figure 2 each of the jacks 10 include the aforementioned lower tubular section 9 which is interiorly threaded to receive the 55 threaded end of a rod section 11 that is provided

on its free end with a head 12 having an anchoring spike 13 integral therewith and adapted to be driven into the top wall or ceiling 14 of the mine as shown. Thus through the medium of the jacks 10 the runners 5 and bar 7 are secured in 5 assembled relation and the runners 5 held at the desired position within the mine.

Extending between the runners 5 is a slide indicated generally by the reference numeral 15 and the slide 15 is adapted to be shifted longitudinally 10 with respect to the runner 5.

The slide 15 comprises a base plate 16 formed on the under side thereof and inwardly from its respective opposite end with grooves 17 to accommodate the runners 5 as will be clear from 15 a study of Figures 1, 5 and 6.

Rising from the base plate 16 at its respective opposite ends and suitably secured to the base plate 16 as at 18 are end plates 19 which support therebetween a pair of rails 20. The rails 20 are secured at their ends to the plates 19 as at 21.

25 Mounted on the slide 15 for movement longitudinally therealong is a carriage indicated generally by the reference numeral 22.

The carriage 22 comprises a top plate or platform 23 to the under side of which is secured as at 24 a relatively narrow block 25.

Secured to the block 25 at intervals as indicated at 26 are a plurality of spaced bearing 30 blocks including intermediate bearing blocks 27 and end bearing blocks 28. The bearing blocks 27 and 28 extend transversely of the platform or plate 23 and the plate 25 and are provided in their upper side with grooves 29 to accommodate 35 the rails 20 of the slide 15 as is perhaps best illustrated in Figure 6.

Also the outer bearing blocks 28 are grooved on their outer side as at 30 to accommodate the 40 end plates 19 when the carriage 22 is moved to the extreme end of the slide 15.

Also on the under side thereof the bearing blocks 27 and 28 are grooved as at 31 to accommodate a plate 32 that is bolted or otherwise secured to the respective bearing blocks as at 33. 45 Thus in this manner are the bearing blocks 27 and 28 fixedly secured relative to one another and the desired spacing therebetween.

Journalled in each of the bearing blocks 27 is a shaft 34 while journalled in each of the bearing blocks 28 is a shaft 35.

50 Each of the shafts 34, 35 is suitably provided, and in a manner as shown in Figure 6, at one end with a sprocket wheel 37 and adjacent a relatively opposite end each shaft 34 is provided 55

with a sprocket wheel 36. At the first named end each of the shafts 34, 35 is squared as at 38.

Also each shaft 34 is in driving engagement with an adjacent shaft 36 through the medium of an endless chain 39 trained over the sprocket 36 of the respective shafts.

Suitably mounted on the top plate or platform 23 of the carriage 22 is an electric motor 40 the armature shaft of which is equipped with a sprocket 41 over which is trained an endless chain 42 that is also trained over the sprockets 36 on the shaft 34. Thus it will be seen that drive is transmitted simultaneously from the motor 40 to the shafts 34 and from these shafts 34 to an adjacent shaft 35.

For shifting the slide 15 on the runners 5 and the carriage 22 on the slide 15 there is provided a single adjusting screw or threaded shaft 43.

The threaded shaft 43 at one end is provided with an operating handle 44 and at its respective opposite end with a substantially ball head 45.

For connecting the last mentioned end to the shaft 46 either with the slide 15 or with the carriage 22 there is provided a shank 46 having on one end thereof a socket 47 through the medium of which and a ball 45 a suitable connection is provided between the screw 43 and the shank 46.

For connecting the shank 46 with either end of the carriage 22 the top plate or platform 23 of said carriage is provided in the respective opposite end edges thereof with a slot 48 to receive the free end of the shank 46 which end is apertured to align with aligned openings 49 provided in the plate 23 above and below each of the slots 48 whereby to accommodate a coupling pin 50.

Further there is provided an internally threaded sleeve 51 having apertured attaching flanges 52 through the medium of which and pairs of sockets 53 provided in the upper end of the end plate 19 of slide 15 the sleeve 51 may be secured on the upper edge of a selected end plate 19, keeper pins 54 passing through the apertured flanges 52 and into the socket 53 to positively secure the sleeve 51 on the selected end plate 19.

Thus it will be seen that with the shank 46 connected with the carriage 22 and the sleeve 51 mounted on one of the end plates 19 as for example shown in Figure 1, the carriage 22 may be shifted lengthwise to the slide 15 in either direction by the turning of the screw 43 in the proper direction.

To utilize the screw 43, shank 46 and sleeve 51 for shifting the slide 15 along the runners 5, the plate 7 is provided with a series of relatively spaced openings 55 through the medium of which and the aforementioned pins 54 the sleeve 51 may be secured in a detachable manner on the plate 7 at the desired adjustment.

Also one of the rails 20 is provided at intervals with slots 56 and into a selected one of said slots the free end of the shank 46 is passed and secured through the medium of the aforementioned coupling pin 50, the said one rail 20 being provided above and below each of the slots 56 with aligned openings 57. Thus, for example, with the screw 46 connected as shown in dotted lines in Figure 1 to the slide 15, said screw may be turned in either direction for advancing or retracting said slide 15.

In using the machine resort is first had to the coal cutting bits 57. The bits 57 are such as illustrated in Figure 12 being provided at one end 75 with squared socket portion 58 through the

medium of which the bits are engaged with the squared ends 38 of the shaft 34 or 35 as may be found desirable.

The first operation is of course the boring of one or more holes in the coal since resort is had to the coal cutting bits 57.

In using the bit 57 drive is transmitted from the motor 40 to the shaft 34 and from the shaft 34 to the shaft 35. Before setting the motor 40 in operation the carriage 22 is of course first shifted to the desired position through the medium of the screw 43. When the carriage 22 has thus been positioned at the desired adjustment the screw 43 is connected with the slide 15 for slowly feeding the slide 15 forwardly as the cutting bit 57 is worked into the coal.

After the boring operation is completed the bits 57 are removed and conveyors such as shown in Figure 13 and indicated by the reference numeral 59 are substituted therefor. The conveyors 59 as shown in Figure 13 are provided at one end with squared pocketed portions 60 with the attachment of the conveyors to the shafts 35. During the reaming of the holes previously bored the slide 15 is advanced by the turning of the screw 43 and after the reaming operation has been completed, screw 43 is turned in a reverse direction for retracting the slide 15.

After a hole has been bored the operation of cutting a slot or kerf is undertaken. To this end there are provided saws 61 and conveying augers 59, hereinafter more fully referred to, the saws 61 acting to cut the kerf or slot and the conveyors 59 acting to remove the cuttings resulting from the sawing operation, the conveying augers 59 trailing the saws 61, as is believed to be apparent.

As shown, each conveying auger 59 is provided at one end thereof with a socket 60 for engagement with one end of a shaft 35.

Each of the saws 61, as best shown in Figures 9 and 10, comprises a shank or core rod 62 on which are disposed in alternation circular saw blades 63 and raker disks 64, the saw blades 63 and raker disks 64 except for the outermost saw blade 63 and raker disk 64, are provided with keys 65 that engage in a way or groove 66 in the shank or core rod 62 for securing the mentioned saw blades and raker disks on the shank or core rod 62 to turn therewith.

The outermost saw blade 63 and raker disk 64 are riveted or otherwise secured together as at 67 and are provided with threaded openings through the medium of which said outermost blade and raker disk are screwed, as a unit, onto the threaded end 62a of the shank or core rod 62 as shown in Figure 9.

As a means of locking the assembled outermost blade 63 and raker disk 64 as a unit on the shaft or core rod 62 there is provided a lock screw 68 as shown in Figure 9.

The aforementioned blade 63 and raker disk 64 are clamped on the shaft 62 between the aforementioned innermost assembled blade 63 and raker disk 64 and a nut 69 threaded on the large diameter of the shaft or core rod 62 as shown in Figure 9. The large diameter of the shaft or core rod 62 is provided with a socket 70 through the medium of which the shaft or core rod is attached to the squared end 38 of a shaft 34.

From the above it will be apparent that after the initial boring operation saws 61 and conveyors 59 are brought into operation to cut the kerf, the saws cutting the kerf, and the conveyors, trailing the saws, conveying the cuttings out-

wardly of the kerf as it is being so cut. Obviously, to advance the saws 61 and the trailing conveyors 59, carriage 22, through the medium of the screw 43, is moved lengthwise along the slide 14. The conveyors 59 thus removing the cuttings from the kerf as it is being thus cut will prevent the saws from becoming clogged, thus insuring smooth operation of the saws during the cutting operation.

10 In connection with the use of the invention it may be further explained that when drilling into soft coal the rotary tool or tools 57 may be of a diameter slightly larger than the diameter of the saws 61 so that immediately following the drilling operations performed by the rotary tool or tools 57 the saws 61 are brought into use for cutting the kerf.

On the other hand when cutting into hard coal it may be necessary to use rotary tools such as tools 57 that are of relatively small diameter for accomplishing the initial boring operation. Under such circumstance, after the boring by the tools 57 has been completed, conveyors 59 of a diameter slightly larger than the saws 61 are resorted to for reaming out the holes in a manner to enlarge the diameters thereof so that the holes will then be of a size to accommodate the saws 61 which are subsequently used for cutting the kerf.

30 From the above it will be seen that I am providing a machine for use in coal mining and that the same will function admirably for undercutting the coal.

What is claimed is:

35 1. In a mining machine of the character described, a slide adapted to be mounted on runners for shifting movement along the runners and relative thereto, said slide including a pair of rails, a carriage mounted on the slide and engageable with the rails to move therealong, a plurality of tool shafts rotatably mounted on the carriage and arranged in pairs, each of said tool shafts being provided at one end for the attachment of a tool thereto, chain sprockets connecting the shafts of each pair, a motor mounted on

the carriage, and chain and sprocket means connecting the shaft of the motor with one shaft of each pair of shafts.

2. In a mining machine of the character described, a pair of runners, a bar extending between and connected to the runners, longitudinally extensible anchoring jacks having lower ends engaging said bar and runners in a manner to secure the bar to the runners and to anchor the runners in set position in the mine, a slide 10 mounted on and extending between the runners, and a tool carriage mounted on the slide for movement therealong and in a direction at right angles to the direction of movement of the slide relative to the runners.

3. In a mining machine of the character described, a pair of runners, a bar extending between and connected to the runners, longitudinally extensible anchoring jacks having lower ends engaging said bar and runners in a manner 20 to secure the bar to the runners and to anchor the runners in set position in the mine, a slide mounted on and extending between the runners, and a tool carriage mounted on the slide for movement therealong and in a direction at right 25 angles to the direction of movement of the slide relative to the runners, and an adjusting screw adapted to be connected with the slide and the carriage for shifting the carriage relative to the slide, and also adapted to be connected with said 30 bar and the slide for shifting the slide relative to the runner.

4. In a mining machine of the character described, a pair of opposed runners, a slide 35 mounted on the runners for shifting movement toward and away from the work, a carriage mounted on the slide to move in a direction at right angles to the movement of the slide, a saw and a conveying auger mounted on the carriage and extending laterally from one side of the carriage in spaced parallelism, and means mounted on the carriage and having driving connection with said saw and conveyor for simultaneously 40 rotating the saw and conveyor.

DAVID R. McCULLOUGH. 45
